UNITED STATES PATENT OFFICE.

JOHN A. MCGUIRE AND RICHARD S. WILLIAMS, OF CELESTE, TEXAS.

DESIGN FOR AN AGRICULTURAL HOEING-WHEEL.

SPECIFICATION forming part of Design No. 29,342, dated September 13, 1898.

Application filed August 16, 1898. Serial No. 688,724. Term of patent 14 years.

To all whom it may concern:

Be it known that we, JOHN A. MCGUIRE and RICHARD S. WILLIAMS, citizens of the United States, residing at Celeste, in the county of Hunt and State of Texas, have invented and produced a new and original Design for an Agricultural Hoeing-Wheel, of which the following is a specification.

This invention relates to a new and original design for an agricultural hoeing-wheel; and it has for its object to provide a design of this character that shall be both useful and ornamental.

The leading feature of the design resides in a circular body having a plurality of flat arms regularly spaced from each other and radiating from the central hub portion of the body, said arms being provided at their outer extremities with laterally-widened blade ends, all of the blade ends lying in the same circular plane.

The minor features of the design are the circular body having a concavo-convex form and the laterally-widened blade ends of the arms being provided with outer beveled edges and with inwardly-convergent inner side edges meeting the straight side edges of the arms, said straight side edges of the arms and the convergent inner side edges of the blade ends forming the boundary-lines of approximately diamond-shaped spaces between the radiating arms.

In the drawings, Figure 1 is a perspective view of the hoeing-wheel embodying the here-

in-described design. Fig. 2 is a plan view 35 thereof. Fig. 3 is a cross-sectional view on the line 3 3 of Fig. 2.

Referring to the accompanying drawings, the numeral 1 designates a circular or disk-like body of a concavo-convex form and provided with a central circular hub portion 2. The said concavo-convex body has projected radially from the hub portion 2 thereof a plurality of regularly-spaced flat arms 3, each of which arms is provided at its outer extremity with a laterally-widened blade end 4, whose outer curved edge is beveled, as at 5, and which is provided with inwardly-convergent inner side edges 6, which meet the straight side edges of the arm. The laterally-widened blade ends 4 of all of the arms 3 lie in the same circular plane, and the straight side edges of the arms and the convergent inner side edges of the blade ends form the boundary-lines of approximately 55 diamond-shaped spaces 7 between the radiating arms.

What is claimed is—

The design for an agricultural hoeing-wheel, herein shown and described. 60

In testimony that we claim the foregoing as our own we have hereto affixed our signatures in the presence of two witnesses.

JOHN A. MCGUIRE.
RICHARD S. WILLIAMS.
